UNITED STATES PATENT OFFICE.

LOUIS P. WHITEMAN, OF NEW YORK, N. Y.

DESIGN FOR A HOSE-REEL.

No. 40,107.

Specification for Design.

Patented June 29, 1909.

Application filed May 4, 1909. Serial No. 493,962. Term of patent 3½ years.

To all whom it may concern:

Be it known that I, LOUIS P. WHITEMAN, a citizen of the United States, residing at New York city, in the county and State of New York, have invented a new, original, and ornamental Design for a Hose-Reel, of which the following is a specification, reference being had to the accompanying drawings, forming a part thereof, and in which—

Figure 1 is a side elevation, and Fig. 2 an edge view of a hose reel embodying my design.

The leading features of my design pertain to the ornamental form and configuration of the side disks of the reel.

I claim:

The ornamental design for a hose reel, as shown.

LOUIS P. WHITEMAN.
